UNITED STATES PATENT OFFICE

LESTER E. BUDD, OF PHILADELPHIA, PENNSYLVANIA

FURNACE-DOOR ARCH.

Application filed July 14, 1921. Serial No. 484,541.

To all whom it may concern:

Be it known that I, LESTER E. BUDD, a citizen of the United States, residing at Philadelphia, in the county of Philadelphia and State of Pennsylvania, have invented certain new and useful Improvements in Furnace-Door Arches, of which the following is a specification.

Much trouble and expense has been caused by the frequent breaking and falling down of the door arches of furnaces.

One object of my present invention is to so make a furnace door arch that it will last for an exceptionally long time.

Another object is to so construct my improved arch that it will be kept comparatively cool and will also protect and form a strong support for the brickwork and wall adjacent thereto.

These objects, and other advantageous ends which will be described hereinafter, I attain in the following manner, reference being had to the accompanying drawings in which—

Figure 1 is a fragmentary elevation viewed from the interior of a furnace showing the side walls in section and illustrating an arch structure made in accordance with my invention,

Figure 2 is a section taken on the line 2—2 of Figure 1,

Figure 3 is a section taken on the line 3—3 of Figure 1,

Figure 4 is a section taken on the line 4—4 of Figure 2,

Figure 5 is a section taken on the line 5—5 of Figure 4,

Figure 6 is a detail top plan view of one of the arch tops shown in Figures 1 to 5 inclusive,

Figure 7 is an inverted plan view of the arch top shown in Figure 6,

Figure 8 is an elevation showing the inner face of said arch top, and

Figure 9 is an elevation showing the outer face of said arch top.

In the drawings I have illustrated my invention in the form of a two-door arch structure.

Referring to the drawings, 10 represents the side walls of a furnace and 11 is the front plate which when used in connection with a boiler is known as the boiler front.

In carrying out my invention I provide a dead plate 12 which has its opposite ends

supported in the side walls 10. This dead plate is preferably made of metal and in the construction as illustrated serves as a support for three hollow piers 13, 14 and 15, the piers 13 and 15 serving as side liners and are preferably embedded part way within in the side walls 10 as shown in Figure 5. These piers 13, 14 and 15 provide upright passages 16, 17 and 18 which extend entirely through the piers; the dead plate 12 having slots 19, 20 and 21 which register respectively with the lower portions of the passages 16, 17 and 18. The pier 14 constitutes a center pier in the form of my invention as illustrated and is spaced between the piers 13 and 15.

Arch tops 22 and 23, which are preferably made of metal, are supported on the tops of the piers; the arch top 22 having its end portion 24 resting upon and covering the top of the pier 13 while the end portion 25 of the arch top 22 rests upon the top of the pier 14. In like manner the end portion 24 of the arch top 23 rests upon the top of the pier 15 and the end portion 25 rests upon the top of the pier 14. Doorways 26 are thus provided by the arch structures above described; the front plate 11 having apertures 27 which register with the doorways 26.

Each of the arch tops 22 and 23 has a forwardly projecting portion 28 which constitutes a forwardly projecting flange which takes the curvature of the top portions of the arch tops as clearly shown in Figures 3 and 9. This flange 28 is shown in abutment with the inner surface of the front plate 11 and in this manner a passageway or channel 29 is formed between the inner surface of the front plate 11 and the surfaces 30 of the arch tops; said channel being arcuate and extending in the direction of the length of the arch tops. The channel 29 is open at its bottom so as to communicate with the space provided by the doorways 26. Each of the arch tops 22 and 23 has a plurality of ports or passageways 31 formed entirely within its thickness; said ports extending from the front surface 30 to the rear or inner surface 32. Thus the ports 31 communicate with the channel 29 and with the interior of the fire box 33 above the dead plate 12 as clearly shown in Figures 2 and 3.

In each of the arch tops the ports 31 are intersected by a longitudinal passageway 34 which is formed entirely within the thick-

ness of the arch top and which is open at its opposite ends so as to communicate with the passages in the piers as shown in Figure 4.

5 In this manner the ports 31 communicate with the channel 29 and with the interior of the fire box 33 and also with the longitudinal passageway 34. The longitudinal passageway is in communication with the passages 10 of the piers and also with the space 35 below the dead plate 12; said space 35 forming the ash pit of the furnace in the usual manner; said front plate 11 having ash doors 36. I 15 preferably locate the ports 31 closer to the top surfaces of the arch tops than to the bottom surfaces thereof so that a comparatively large portion of the metal is present directly over the doorways and the strength of the arch tops is not impaired.

20 I have found by actual use and installation that arch structures made in accordance with the above will last, even under severe operating conditions, for a far greater time than other known metallic arch structures.

25 The arrangement provides cooling means since air can circulate through the piers, arch tops and dead plate so that the temperature will be equally distributed at practically all portions of the arch structure as is believed to be obvious from the illustration and foregoing description. In addition to this, the furnace front is kept comparatively cool since the provision of the channel 29 serves as a breach in the arch top structure 30 and also serves to provide a cooling space between the major portions of the arch top and front plate 11. In addition to this, the brickwork above the arches and also adjacent the ends thereof will be protected and 40 consequently will last for a great length of time.

While I have described my invention as taking a particular form, it will be understood that the various parts of my invention 45 may be changed without departing from the spirit thereof, and hence I do not limit myself

self to the precise construction set forth, but consider that I am at liberty to make such changes and alterations as fairly come within the scope of the appended claims.

Having thus described my invention, what I claim as new and desire to secure by Letters Patent is:—

1. A furnace arch structure including a top, piers supporting the top, a dead plate supporting the piers, the piers having upright passages communicating with the ash pit and with ports leading to the fire box, the dead plate having slots communicating with the upright passages, and the top having ports extending from front to rear thereof communicating with the doorway and the fire box.

2. A furnace arch structure including a top, piers supporting the top and having passages communicating with the ash pit, the top having ports communicating with the doorway and the fire box and a transverse passage communicating with the ports and with the passages in the piers.

3. A furnace arch structure including a top, piers supporting the top and having passages communicating with the ash pit, the top having a forwardly extending flange abutting the front plate and forming a channel communicating with the doorway, ports communicating with the channel and the fire box and a passage intersecting the ports and communicating with the passages in the piers.

4. A furnace arch structure including a top having ports communicating with the doorway and the fire box and a transverse passage intersecting the ports.

In testimony whereof I have signed my name to this specification in the presence of two subscribing witnesses.

LESTER E. BUDD.
